(57) **CLAIM**

The ornamental design for a broom, as shown and described.

DESCRIPTION

FIG. 1 is a front view of a broom showing our new design;

FIG. 2 is a top plan view thereof;

FIG. 3 is a bottom plan view thereof;

FIG. 4 is a side elevational view thereof; and,

FIG. 5 is perspective view thereof, with the broken lines showing a handle and bristles being for illustrative purposes only and forming no part of the claimed design.
